(57) **CLAIM**

The ornamental design for a display screen or portion thereof with graphical user interface, as shown and described.

DESCRIPTION

FIG. 1 is a front view of a display screen or portion thereof with graphical user interface showing my new design; and, FIG. 2 is an enlarged view of the encircled portion in FIG. 1.

The outer perimeter illustrated by a pair of broken lines in FIG. 1 depicts a display screen or portion thereof and forms no part of the claimed design. The dot-dash broken lines that encircle the portion of the drawing disclosure that is illustrated in an enlargement forms no part of the claimed design. The remaining broken lines in the drawings depict portions of the graphical user interface that form no part of the claimed design.

1 Claim, 2 Drawing Sheets

FIG. 1

English $\leftrightarrow$ Korean $\times$

Next is beautifully crafted

With their slim, seamless, full metal and glass construction, the sleek, ultrathin edged Galaxy S6 and unique, dual curved Galaxy S6 edge are crafted from the finest materials. And while they may be the thinnest smartphones we've ever created, when it comes to cutting-edge technology and flagship Galaxy experience, these 5.1" QHD Super AMOLED smartphones are certainly no lightweights.

Next is smarter charging

When you're on the Galaxy S6 edge feed, you watch 2 hours and 20 minutes. And with their built-in battery, the Galaxy S6 and Galaxy S6 edge offer you all the convenience of charging without the need to plug in - ensuring you're always powered and ready for what's next.

2

Next is better camera

Whether you're into capturing stunning 'selfies' or spectacular sunsets, the 5-megapixel front camera and 16-megapixel rear camera are ready when you are. With a launch time of just 0.7 seconds, you can capture more of your favourite moments, as they happen. And thanks to its Optical Image Stabilisation, fast tracking auto focus and bigger, f1.9 aperture for better low light results, every shot will be as amazing as the next.

Next is crisper

Protected by the very latest Gorilla Glass, the stunning 5.1" QHD Super AMOLED display, with real RGB colour, delivers images and film so life-like, your only problem will be, what to enjoy next.
